DESIGN FOR A LEATHER STRAP BUCKLE
MEMBER

Ludwig Oppenheimer, Los Angeles, Calif.

Application December 29, 1947, Serial No. 143,402

Term of patent 3½ years

(Cl. D17—1)

To all whom it may concern:

Be it known that I, Ludwig Oppenheimer, a citizen of the United States, residing in the city and county of Los Angeles and State of California, have invented a new, original, and ornamental Design for a Leather Strap Buckle Member, of which the following is a specification, reference being had to the accompanying drawing, forming part thereof.

Fig. 1 is a perspective view of a leather strap buckle member showing my new design.

Fig. 2 is a top plan view.

Fig. 3 is a section on line 3—3 of Fig. 2.

I claim:

The ornamental design for a leather strap buckle member, substantially as shown.

LUDWIG OPPENHEIMER.
